SHOE WITH INNERSOLE PROVIDING ARCH SUPPORTING FLAP

Fred J. Diamant, New York, N. Y.

Application May 11, 1945, Serial No. 593,121

5 Claims. (Cl. 36—8.5)

1

This invention relates to shoe constructions and more particularly to a novel innersole providing an integral support for the arch of a foot.

It is among the objects of this invention to provide a shoe innersole having a portion integral therewith shaped to form a support for a foot arch; to provide a novel shoe innersole having an integral foot arch support and continuous stitching margin of substantial width; to provide a shoe innersole having a flap integral therewith adapted to form a support for a foot arch and a member secured to the innersole adjacent the flap to provide a continuous stitching margin and a pocket for resilient filler material; and to provide a shoe construction comprising a novel foot arch supporting innersole.

These and other objects, advantages and novel features of the invention will become apparent from the following description and the accompanying drawing. In the drawing:

Fig. 1 is a top plan view of a shoe innersole constructed in accordance with the invention.

Fig. 2 is a side elevational view of the innersole shown in Fig. 1.

Fig. 3 is a bottom plan view of the innersole shown in Fig. 1.

Fig. 4 is a top plan view, partly broken away, of a shoe embodying the innersole construction shown in Figs. 1, 2 and 3.

Fig. 5 is an inside elevation view of the shoe illustrated in Fig. 4.

Fig. 6 is a sectional view of the line 6—6 of Fig. 4.

Fig. 7 is a sectional view on the line 7—7 of Fig. 4.

Generally speaking, according to the present invention, a shoe innersole is cut from leather, composition, or any other suitable material in such manner as to provide a stitching margin of substantial width extending around the major portion of the periphery of the innersole. Adjacent the inside of the shank portion of the sole, the stitching margin is cut back and a flap is formed, integral with the sole, extending outwardly and upwardly to form a support for a foot arch. To complete the stitching margin for the sole adjacent such flap, a piece of suitable material such as leather, composition or other material, is secured to the underside of the innersole adjacent the flap and made functionally contiguous with the sole. Cushioning material is secured to the underside of the supporting flap; or the pocket formed between the flap and the piece of material secured to the sole may be filled with a suitable filler. Preferably, a shank stiffener is

inserted between the bottom of the innersole and the piece of material secured thereto.

To form a "stitched down" shoe, a shoe upper is secured to the innersole by having an outwardly turned flap thereon stitched to the stitching margin of the innersole. A welt may be secured to the upper surface of such outwardly turned flap. In the completed shoe, the upper edge of the flap rests against the instep portion of the upper to form a foot conforming support for the foot arch.

Referring to Figs. 1, 2 and 3 of the drawings, an innersole 10 is illustrated as provided with a continuous stitching margin, the inner edge of which is indicated by the dotted line 11. Sole 10 has a toe portion 12, a shank portion 13 and a heel portion 14. A novel feature of my invention resides in the cavities molded or otherwise formed into the sole and heel portions thereof. Thus, the cavities 12' and 14', are formed in the sole 10 shaped to accommodate the corresponding ball or curved portions of the sole and heel of the foot. This, in combination with the raised shank portion 13 of the innersole, as will be described, constitutes a form fitting and comfortable innersole construction for the shoe. The inner side of the shank portion is cut away as indicated at 15 and 16 and a flap 17 is formed integrally and extending outwardly and upwardly from sole 10. Flap 17 is bevelled outwardly from its junction with sole 10, as indicated more particularly at 37 in Fig. 7 of the drawing.

To complete the stitching margin for the innersole adjacent the cut away portion, a piece of suitable material 20, such as leather or composition, is secured to the underside of the sole adjacent the inside of shank portion 13. Piece 20 is suitably bevelled as indicated at 21 in Fig. 7, and has an outer periphery 22 which serves as a continuation of the stitching margin of sole 10. Sole member 20 is secured to sole 10 by any suitable means, such as being adhesively secured thereto, and is thereby made a functionally integral part of the sole.

Preferably, a piece of cushioning material 25, such as sponge rubber, is secured to the underside of flap 17, with its inner edge extending between member 20 and flap 17 or sole 10. Desirably, a sole stiffener 26 extends longitudinally of shank portion 13, being adhesively secured between sole 10 and sole member 20.

Referring to Figs. 4 through 7, a shoe upper 30 of flexible material, such as leather or similar material, is provided with an out turned flap 31 extending around its entire lower periphery. Flap 31 is placed in juxtaposition with the stitch-

ing margin 11 of sole 10 and a welt 32, extending completely around the shoe, is placed on top of flap 31. An outer sole 35 is then placed against the underside of innersole 10, and flap 31, welt 32, innersole 10 and outer sole 35 are then secured together by suitable means such as stitching indicated at 36.

As indicated in Figs. 4, 5 and 7, the upper thin edge 37 of flap 17 rests against the instep portion 38 of upper 30, to form a support for a foot arch. The purpose of the support for the foot arch is not to lift the foot from the inside to the outside, but to provide a firm support for the foot which is molded according to the contour of the foot. Such arched support, in combination with the sole and heel cavities 12' and 14' provide particularly healthful and comfortable foot support. It is feasible to utilize other materials than leather for the innersole 10, as for example, a composition or plastic material.

Hitherto, it has been difficult or costly to provide an innersole support of the nature afforded by the present invention in a shoe of the stitched on type or in a slip lasted shoe, as the provision of the foot arch support prevented forming a complete stitching margin around the innersole. However, by the provision of member 20 continuing the stitching margin of sole 10 adjacent shank portion 13, the present invention provides such a foot arch support for fabrication into the shoe by conventional methods. The resultant shoe is a healthful, foot supporting shoe of attractive appearance.

While a specific embodiment of the invention has been described to illustrate the application of the principles thereof, it will be obvious to those skilled in the art that the invention may be otherwise embodied without departing from such principles.

What is claimed is:

1. A shoe innersole having toe, shank and heel portions and a stitching margin of substantial width and uniform thickness around its entire periphery, and a tapered flap projecting outwardly and upwardly from the inner edge of said stitching margin at the inside of said shank portion to form a support for the foot arch integral with the sole, said flap having a base thickness substantially equal to the thickness of said innersole and tapering in thickness outwardly from its base; and a tapered sole member secured to the underside of said shank portion and underlying only said flap and a part of said shank portion, the outer edge of said member providing a continuation of said uniformly thick stitching margin along the inside of said shank portion.

2. A shoe innersole having toe, shank and heel portions and a stitching margin of substantial width and uniform thickness around its entire periphery, and a tapered flap projecting outwardly and upwardly from the inner edge of said stitching margin at the inside of said shank portion to form a support for the foot arch integral with the sole, said flap having a base thickness substantially equal to the thickness of said innersole and tapering in thickness outwardly from its base; a tapered sole member secured to the underside of said shank portion and underlying only said flap and a part of said shank portion, the outer edge of said member providing a continuation of said uniformly thick stitching margin along the inside of said shank portion; and a cushioning pad secured to said flap and inserted between said sole member and said shank portion.

inwardly of the inner edge of said stitching margin.

3. A shoe innersole having toe, shank and heel portions and a stitching margin of substantial width and uniform thickness around its entire periphery, and a tapered flap projecting outwardly and upwardly from the inner edge of said stitching margin at the inside of said shank portion to form a support for the foot arch integral with the sole, said flap being bevelled inwardly, and having a base thickness substantially equal to the thickness of said innersole and tapering in thickness outwardly from its base; and a sole member secured to the underside of said shank portion and underlying only said flap and a part of said shank portion, said member providing a continuation of said uniformly thick stitching margin along the inside of said shank portion; said sole member being bevelled along its inner edge for juxtaposition with the juxtaposed portion of said sole, whereby the thickness of said sole is substantially not increased by said sole member.

4. A shoe comprising, in combination, an innersole having toe, shank and heel portions, and a peripheral stitching margin of substantial width and uniform thickness, said stitching margin being cut away at the inside of said shank portion in such a manner as to provide a bevelled flap projecting outwardly and upwardly from the inner edge of said stitching margin at the inside of said shank portion, said flap having a base thickness substantially equal to the thickness of said innersole and tapering in thickness outwardly from its base; a tapered sole member secured to the underside of said shank portion and underlying only said flap and a part of said shank portion, said member providing a continuation of said uniformly thick stitching margin along the inside of said shank portion; and an upper stitched to such stitching margin around its entire periphery; the upper edge of said bevelled flap engaging the instep portion of said upper to form a curved support for the foot arch.

5. A shoe comprising, in combination, an innersole having toe, shank and heel portions, and a peripheral stitching margin of substantial width and uniform thickness around its periphery, said stitching margin being cut away at the inside of said shank portion in such a manner as to provide a bevelled flap projecting outwardly and upwardly from the inner edge of said stitching margin at the inside of said shank portion, said flap having a base thickness substantially equal to the thickness of said innersole and tapering in thickness outwardly from its base; said sole being bevelled outwardly from such cut away section in continuation of the bevel of said flap; a sole member secured to the underside of said shank portion and underlying only said flap and a part of said shank portion, said member providing a continuation of said uniformly thick stitching margin along the inside of said shank portion, said sole member being bevelled along its inner edge for juxtaposition with the bevelled portion of said sole, whereby the thickness of said sole is substantially not increased by said sole member; an upper engaging such stitching margin around its entire periphery; and stitching uniting said stitching margin and said upper; the upper end of said bevelled flap engaging the instep portion of said upper to form a curved support for the foot arch.
